UNITED STATES PATENT OFFICE

WILLIAM ANDREW FINLEY, OF VALDOSTA, GEORGIA

HEATER

Application filed August 19, 1931. Serial No. 558,171.

This invention relates to a combined radiation unit and sanitary fixture, the primary object of the invention being to provide a sanitary fixture and a unit of radiation in a single article, thereby conserving space and improving appearance.

An important object of the invention is to utilize space and simplify installation, thereby eliminating one fixture by combining the fixture and radiation unit, the fixture being so constructed that a vent will be provided where a gaseous radiation unit is used.

Another object of the invention is the provision of a heating unit which is of any varied radiation unit and may be combined with sanitary fixtures in general, two of which being lavatories and bath tubs.

With the foregoing and other objects in view, which will appear as the description proceeds, the invention resides in the combination and arrangement of parts and in the details of construction hereinafter described and claimed it being understood that changes in the precise embodiment of the invention herein disclosed, may be made within the scope of what is claimed, without departing from the spirit of the invention.

Referring to the drawings:

Figure 1 is a front elevational view of a basin or stand constructed in accordance with the invention.

Figure 2 is a side elevational view of a basin or stand, illustrating the opening or space for containing the radiation unit.

Figure 3 is a bottom plan view thereof.

Figure 4 is a transverse sectional view through the pedestal of the fixture, constructed in accordance with the invention.

Figure 5 is a plan view of the fixture.

Figure 6 is a plan view illustrating the tank or water chamber on which the bowl or fixture rests when the bowl of the fitting is not equipped with an integral water chamber.

Figure 7 is a sectional view taken on line 7-7 of Figure 6.

Figure 8 is a view illustrating a tray to be positioned under the flange of a basin fitting when the basin is not equipped with a partition such as shown by Figure 1.

Figure 9 is a sectional view taken on line 9-9 of Figure 8.

Figure 10 is a modified form of basin.

Referring to the drawings in detail, the basin comprises a pedestal 5 which is hollow, the front wall thereof being provided with a compartment 6 so constructed that a heat radiation unit may be securely held therein.

The basin 7, which forms an integral part of the pedestal as shown by Figure 1 of the drawings, is formed with a water chamber 7' which is fed with water from the hot water supply pipe 8, through the opening 9 of the pipe.

It will of course be understood that this pipe 8 passes directly through the water chamber 7', so that a quantity of water may pass into the chamber to maintain the upper portion of the basin of the fixture cool, and prevent over-heating of the basin.

The compartment 6 is especially designed for accommodating a heat radiation unit of the gaseous fuel type, and as shown includes a pipe 10 through which the products of combustion may pass to the atmosphere.

It will of course be understood that the pipe 10 will connect with a vent pipe so that the products of combustion may be carried to a point exteriorly of the room in which the fitting is positioned.

While I have described a heat radiation unit of the gaseous fuel type it is to be understood that various other types of radiation units, such as electricity, may be used without departing from the spirit of the invention.

Figure 6 of the drawings illustrates a modified form of the invention, and embodies a water chamber 11 which is designed to be fitted under a basin, should it be desired to use this type of radiation with a water basin and pedestal wherein the basin is not provided with an integral bottom member corresponding to the bottom member 12 of the basin shown by Figure 1 of the drawings.

The hot water feed pipe, which is indicated by the reference character 12', extends through the water chamber 11, where it is supplied with a spigot 13, the pipe 12' being formed with an opening 14, through which water may pass into the chamber 11.

A tray such as shown by Figure 8 of the drawings may be used in place of the water chamber 11, and as shown this tray comprises a body portion 15 that has an upstanding flange 16 and an upstanding flange 17, the flange 17 being substantially short as compared with the flange 16.

It might be further stated that the heat radiation chamber includes a rear wall 18 disposed directly at the rear of the radiation chamber, the rear wall acting to reflect the heat from the radiation chamber forwardly into the room in which the fitting is provided.

- 15 While I have shown and described the fitting as in the form of a wash stand and basin, it is to be understood that it is within the scope of the invention to construct bath tubs, lavatories or the like in such a way that radiation units may be employed in connection therewith for heating the room.
- 20 Having thus described the invention, what is claimed is:

25 A wash basin fixture comprising a hollow pedestal having an opening in the front wall thereof, a body portion fitted in the opening, a partition in the body portion dividing the body portion into a rear heat radiating chamber, the partition being disposed at a point 30 intermediate the front and rear walls of the body portion, and said partition having upper and lower openings to allow heat to be directed forwardly through the partition, and said partition being disposed in spaced 35 relation with the front wall of the pedestal.

In testimony that I claim the foregoing as my own, I have hereto affixed my signature.

WILLIAM A. FINLEY.
